CLAIM

We claim the ornamental design for a cover for filler flats containing eggs, as shown and described.

DESCRIPTION

FIG. 1 is top perspective view of a cover for filler flats containing eggs in accordance with our design;

FIG. 2 is a front elevational view thereof, with the rear elevational view being a mirror image thereof;

FIG. 3 is a right side elevational view thereof, with the left side elevational view being a mirror image thereof;

FIG. 4 is a top elevational view thereof; and,

FIG. 5 is a bottom elevational view thereof.
